(57) **CLAIM**

The ornamental design for a cosmetic puff, as shown and described.

DESCRIPTION

FIG. 1 is a perspective view of the cosmetic puff; the broken lines in FIG. 1 illustrate a user's hand and form no part of the claimed design;

FIG. 2 is another perspective view of the cosmetic puff, this view depicting a state of rest of the cosmetic puff;

FIG. 3 is a front view thereof (where a rear view is a mirror image of this front view);

FIG. 4 is a left side view thereof (where the right side view is a mirror image of this left side view);

FIG. 5 is a top view thereof (where the bottom view is a mirror image of this top view); and,

FIG. 6 is a top view of the cosmetic puff in an alternate position folded.

Line surface shading resides on all of the figures in order to represent the character and contour of the surfaces of the cosmetic puff.
